UNITED STATES PATENT OFFICE.

WILLIAM S. OSBORNE, OF MARIETTA, PENNSYLVANIA.

GRINDING OR PULVERIZING MILL.

No. 845,661.

Specification of Letters Patent.

Patented Feb. 26, 1907.

Application filed September 17, 1904. Serial No. 224,870.

To all whom it may concern:

Be it known that I, WILLIAM S. OSBORNE, a citizen of the United States of America, and a resident of Marietta, in the county of Lancaster and State of Pennsylvania, have invented certain new and useful Improvements in Grinding or Pulverizing Mills, of which the following is a specification.

This invention relates to improvements in crushing or pulverizing mills in which the material is fed between a revolving ring and crushing-rolls working within said ring.

The objects of my invention are to provide a mill in which the material is fed between crushing-rolls and crushing-rings and to provide, in connection with said crushing devices, a rotary sifting device which is so arranged that the material which is too coarse to pass through the sieves is elevated by the rotation 20 of the sieves, so as to be again fed between the crushing-surfaces.

In the preferred embodiment of my invention there are three rolls of different sizes on a driving-shaft, which rolls impart movement to the crushing-rings, and these rings in turn impart motion to spring-actuated crushing-rolls which are held against said rings in grinding contact therewith. As the material is fed to these rolls it is pulverized 30 and passes out from the grinding-chamber onto a rotary sieve, and that part of the material which is sufficiently pulverized passes through the screen to be delivered to any proper receptacle or vehicle. The coarser 35 material is delivered over the edges of the screens into rotary pockets forming part of the rotary screens, and as the screens and pockets are rotated this coarser material is brought up to a point where it may fall 40 through hoppers and again delivered between the crushing-rolls and the crushing-rings.

My invention therefore consists in the pulverizing-mill which is shown in its preferable embodiment in the accompanying drawings, 45 as will now be hereinafter described and then definitely claimed.

In the drawings which accompany and form part of this application, Figure 1 is a 50 vertical central section through my entire mill. Fig. 2 is an end elevation of the same with parts broken away in order to better illustrate the construction. Fig. 3 is a vertical section with parts broken away in order

to show the pockets provided by apparatus 55 for returning the coarse material.

Referring now to the details of the aforesaid drawings by numerals, the main frame comprises two heavy castings 1 and 2 on opposite sides of the machine, each being supported by a pair of standards 3 and 4. The main castings 1 and 2 are formed with bearings 6 and 7 for the main or driving shaft 8, 60 which is driven by balanced pulleys 9 and 10 from any suitable source or power. The main castings 1 and 2 are of peculiar formation in that each one of them is formed, as shown in Fig. 2, with a hollow end portion, in each of which is supported bearings for supplemental shafts, which will be hereinafter 65 more particularly described.

To the interior surfaces of each of the main castings 1 and 2 is secured plates 14 and 15, which form the walls of the grinding-chamber. These plates 14 and 15 are preferably 70 bolted to the main castings 1 and 2 and are provided with hubs 17 and 18, which form additional bearings for the main shaft 8. To these plates 14 and 15 are secured cylindrical casings 20 and 21, and to these casings 75 is secured the exterior frame, which comprises the outer plates 24 and 25, connected by the curved sheets 27, 28, 29, and 30, which are bolted or riveted together, as clearly seen at 32. The lower curved sheets 29 and 30 80 are formed into an open-ended spout 33, from which the material is collected in any suitable receptacles, as may be necessary.

Within the grinding-chamber, between the plates 14 and 15, is a series of three grinding- 85 rolls 35, 36, and 37, which are firmly keyed or otherwise fixed to the main shaft 8, so as to be rotated thereby. Each of these rolls 35, 36, and 37 supports an independent grinding-ring, these rings being designated by the 90 numerals 40, 41, and 42. These three rings are supported by the aforesaid rolls 35, 36, and 37 and are rotated by said rolls whenever power is applied to the pulleys 9 and 10. In addition to supporting the rings 40, 41, 95 and 42 the rolls 35, 36, and 37 also act to 100 grind or pulverize any material that is carried up to the rolls by the rings; but in order to more effectively pulverize the material I 105 employ two other sets of rolls, which I will now describe, together with their supporting-shafts. As indicated in Fig. 2, there are two supplemental shafts, (designated 44 and 45,) 110

and on each of these shafts are supported three rollers substantially identical with the rollers 40, 41, and 42 and which I have designated by the numerals 47 and 48. These 5 rollers are not used to drive the rings, but instead are driven by the rings during the process of grinding or pulverizing, and they must therefore be held against the rings with considerable pressure. This may be accomplished in a number of ways, as by springs or 10 weights; but I much prefer the simple way illustrated in my drawings, and which consists of the following parts: For each shaft 44 and 45, at opposite ends thereof, I provide 15 movable bearings 50 and 51, which are arranged to fit and slide within the openings 53 and 54, formed within the main castings and which openings have been hereinbefore mentioned. Each bearing is provided with a 20 spindle or shank 56, having a head 57, around which spindle or shank a spiral spring 59 is placed, either before or after the head is secured to the spindle or shank 56. Slipped over the spindle or shank 56 is a U-shaped 25 open member 60, having projecting portions at its upper end forming a seat for the spring 59. The opposite end of said member 60 is provided with a shank 61, which projects through an opening 62 in the main frame, 30 and on the exposed end of this spindle or shank is screwed an adjusting-nut 65, by which the tension of the spring may be easily adjusted. The shanks 56 of these open-ended members 60 are first slipped through 35 their openings 62, and the bearings may then be slipped in the open-ended main frame, the nut 65 being adjusted after the parts are assembled. It will be understood that the bearings 50 and 51 at each end of each shaft 40 is provided with the spring-actuated device 40 just described, so that each shaft may be adjusted at each end thereof in order that more or less pressure may be brought to bear between the rolls 47 and 48, carried by their 45 respective shafts.

It follows from the foregoing description that when power is applied to the pulleys 9 and 10 and the shaft 8 rotated the rotary movement is transmitted to the upper supporting-rolls 35, 36, and 37 and motion is transmitted from these rolls so as to rotate the grinding-rings 40, 41, and 42 around the said rolls. As these rings rotate the grinding-rolls 47 and 48, which are held by the 50 springs 59 in contact with the rings 40, 41, and 42, are rotated by said rings, and as the material to be pulverized is fed into the grinding-cylinder it is crushed in its passage between the various rolls and their respective rings. It will thus be seen that I provide three driving-rolls which support the grinding-rings and that the latter rotate the main grinding-rolls which are held by spring pressure against the interior walls of the rings 55 as they are driven by the latter; and it will

also be observed that, inasmuch as the three grinding-rolls are of different sizes, the center one being much the larger, the speed of rotation given to the three rings 40 and 42 is somewhat slower than that given to the center ring 41. I desire to call particular attention to these crushing-rolls and to their method of operation. In addition to the fact that the two outside sets of rolls are smaller in size and therefore rotate their respective rings at a lower speed, because I arrange them in a series and cause the grinding to be done first by the smaller and afterward by the larger rolls, I am enabled to provide a gradual reduction-mill which gives exceedingly fine results. By referring again to Fig. 1 of the drawings it will be observed that there are two retaining-rings 63 and 64, one of which is secured to the left-hand grinding-ring 40 and the other to the right-hand grinding-ring 42. It will also be observed that these rings lap over the space between the outside grinding-rings and their grinding-rolls, so that it is impossible for any material to pass out between the rolls and their rings at this point. Hence the material which has been fed by the delivery-spouts (94 herein-after referred to) is compelled after receiving a preliminary crushing by the outside rolls to pass inwardly toward the center set of rolls. Of course if any material has been crushed fine enough by the outside rolls this fine material passes out of the two spaces 40^a and 41^a between the inner ring and the two outside rings; but the material which has not been ground fine enough is forced between the larger center rolls and their rings and is thus ground until it is fine enough to pass out of the said restricted openings 40^a and 41^a. To state the matter in a different way, the object in using rolls of different diameters is to permit the use of a middle grinding-ring having a grinding-surface of greater diameter than the grinding-surfaces of the side rings, in order that the grinding-surface of the middle ring may be so located as to facilitate the delivery of material from the side rings to the middle ring—that is to say, by this construction the grinding-surface of the middle ring at the lower portion of the ring is below the grinding-surfaces of the side rings, so that material can fall from the side rings to the middle ring, and also since the rings are concentric the centrifugal action tends to carry material from the side rings to the middle ring about their entire peripheries, the grinding-surface of the middle ring being farther from the axis of the rings than the grinding-surface of the side rings. There is also a differential movement of the adjacent lateral surfaces of the grinding-rings due to their different peripheral speeds, which facilitates the passage of grinding material through the spaces between the rings. The result of the construction described is that the side rings 100

105

110

115

120

125

130

135

when rolled give a preliminary crushing which is not as fine as that due to the larger and more powerful center rolls. I deem this gradual crushing as of considerable importance. After the crushed material passes out of the openings 40^a 41^a it passes onto screens that will now be described.

Secured to the outer plates 24 and 25 of the exterior casing are two bearings 43 and 46, and supported in these bearings is a shaft 66, to which is secured a sprocket-wheel 67, from which motion is received from a sprocket-wheel 68 on the main shaft 8 by means of the sprocket-chain 69. Near the ends of the supplemental shaft 66 and keyed thereto are two gear-wheels or pinions 70 and 71, and these gears or pinions mesh with internal gears, forming rings 72 and 73 of circular form. These rings 72 and 73 are supported on the aforesaid pinions 70 and 71 and are prevented from lateral motion by means of two idlers 75 and 76. (Shown in Fig. 2 as being supported on bearings 77 and 78.) The construction is such that whenever motion is transmitted from the main shaft 8 to the supplemental shaft 66 by means of the sprocket-wheels 67 and 68 and the sprocket-chain 69 the gears 70 and 71 rotate the internally-gearred rings 72 and 73. To these rings are secured on each side of the mill side frames 78 and 79, which support between them the double screens or sieves 80 and 81, the two side frames being held together by bolts 82 and 83, as clearly shown in Fig. 1. The side frame 78 and 79 are preferably octagonal in form, as indicated in Fig. 2, and are formed with pockets 84 and 85, which are divided by partitions 96, as shown in dotted lines in Fig. 2. The outer edges of these pockets are closed by rings 87 and 88, which prevent any of the material from escaping between the pockets and the outer plates 24 and 25 of the exterior casing. To these rings 87 and 88 are also secured rings 89 and 90, which point inward, so as to deflect the material away from the outer plates 24 and 25. As these rings, with their pockets 84, are rotated the coarse material which has not been pulverized sufficiently passes out of the sides of the screens into the said pockets, and as the pockets rotate the coarse material is carried by the divisional walls 96 of the pockets until the pockets reach such a position that the material will fall therefrom by gravity. In order to catch the material as it falls and feed it back into the grinding-chamber again, I employ a pair of hoppers 92 and 93, which are supported on the shaft 66 near the opposite ends thereof, as clearly seen in Fig. 1. These hoppers are of the peculiar shape shown in dotted lines in Fig. 2 and are contracted at their lower ends so as to be formed in delivery-spouts 94 immediately over the right-hand sets of rolls, as viewed in Fig. 2. Hence as the material drops onto the screens

and is sifted thereby any material which is too coarse to pass through the screens passes into the pockets 84 and by them carried to the upper end of the machine, where these coarse particles are dropped into the hoppers 70 and 93 and again delivered to the grinding-rolls to be reground. It will be noticed that the inclination of the partitions 96 is such that it will hold the material until the partition is over the upper enlarged end of the hopper before the material can slide off of the partition-walls. The uncrushed material is in the first instance fed to the hoppers 92 and 93 through spouts or chutes 96 and 97, which pass through the outer plates 24 and 25, as seen in Fig. 1.

It is believed a fair description of the operation of my mill has been given in connection with the detailed description of the various parts, yet it may be best to state that as the material leaves the hoppers 92 and 93 it falls immediately over both of the outer right-hand sets of grinding-rolls, as seen in dotted lines in Fig. 2, and as these grinding-rolls rotate in the direction shown in the arrow in said figure the material is given a preliminary crushing in its passage between the surfaces of said rolls and the grinding-rings 40, 41, and 42. The material which is fine enough to escape passes through the openings 40^a and 41^a onto the screens 82 and 83 and is sifted thereby; but the material which is not fine enough to escape is carried around by the rings 40, 41, and 42 (which it will be remembered revolve at different speeds) and passes between the other larger set of grinding-rollers. Of course a portion of the material is also carried by centrifugal force up to the upper set of rolls 35, 36, and 37 and is ground between these rolls and the grinding-rings. The material which passes out of the spaces 40^a and 41^a onto the screens is sifted and the material is delivered out of the spout or hopper 33, while those portions which are too coarse to be sifted pass through the openings at the ends of the screens into the pockets 84 and are carried by the walls 86 thereof up to the upper side of the machine, from which it is again delivered to the hoppers 92 and 93 to be again fed to the grinding-rolls, as before described.

It will be observed that although two sets of grinding-rolls are held by springs against the grinding-rings the grinding-rings are supported by the upper set of rolls, which are carried on a shaft which has no movement other than the necessary rotary motion imparted by the driving-pulleys 9 and 10. The grinding-rings are therefore very steady in rotation, and I consider this a decided advantage and of great importance.

I am well aware of United States Patent No. 673,856, granted May 7, 1901, to H. L. Kent, but regard my invention as essentially different therefrom. By employing a plurality of

sets of grinding-rolls and obtaining the gradual reduction hereinbefore described I obtain vastly different results than are obtained by said patented mill.

5. It is obvious that modifications and variations may be made in the form of my invention without departing from the essential features thereof, and I therefore refer to the following claims to point out the scope of my invention, and in some of these claims I have referred to a series or plurality of rolls on the main or driving shaft. It will be obvious that these rolls may be formed in one integral piece and keyed to the shaft and yet be a series so far as their shape and driving effect is concerned. I therefore intend the claims to cover the three rolls on the driving-shaft whether said rolls are integral or separate.

What I claim as my invention is—

20. 1. In a pulverizing-mill, a series of independent revolving rings, in combination with a series of rolls located within and imparting rotary movement to said rings, the rolls being of different sizes whereby a gradual reduction is attained, substantially as described.

25. 2. The combination in a pulverizing-mill, of a series of independent revolving rings, a series of rolls located within and imparting rotary movement to said rings, and a series 30 of spring-mounted grinding-rolls also coacting with said rings, the rolls being of different sizes whereby a gradual reduction is attained, substantially as described.

35. 3. The combination in a pulverizing-mill, of a series of independent grinding-rings, a main shaft, a series of rolls of different size on said shaft, said rolls supported within and imparting rotary movement to said rings, supplemental shafts, spring-mounted bearings for said shafts, and grinding-rolls carried by said shafts coacting with the series of grinding-rings, the rolls being of different sizes whereby a gradual reduction is attained, substantially as described.

45. 4. The combination in a pulverizing-mill, of a series of grinding-rings, a main shaft, a series of rolls on said shaft, said rolls supported within and imparting rotary movement to said rings, supplemental shafts, 50 spring-mounted bearings for said shafts, grinding-rolls carried by said shafts coacting with the series of grinding-rings, and means for preventing the crushed material from passing out of the outside rings, substantially as described.

55. 5. The combination in a pulverizing-mill, of a series of grinding-rings, a main shaft, a series of rolls on said shaft, said rolls supported within and imparting rotary movement to said rings, supplemental shafts, 60 spring-mounted bearings for said shafts, grinding-rolls carried by said shafts coacting with the series of grinding-rings, and plates or rings for preventing the crushed material

from passing out of the outer sides of the outside rings, substantially as described.

6. The combination in a pulverizing-mill, of a driving-shaft, a grinding-ring, a roll carried by said shaft and imparting rotary movement directly to said ring, supplemental shafts, a grinding-roll supported on each of said shafts coacting with said ring to grind material between said rolls and said ring, and a frame having openings within which the bearings of said shafts are located, and 70 spring-mounted devices also located within the openings in said frame for forcing the last-mentioned rolls against said ring, substantially as described.

7. The combination in a pulverizing-mill, 80 of a driving-shaft, a series of independent grinding-rings, a series of rolls carried by said shaft and imparting rotary movement to said rings, supplemental shafts, a series of rolls supported on each of said shafts coacting with 85 said rings and a frame having openings in which the bearings of said shafts are situated, substantially as described.

8. The combination in a pulverizing-mill, 90 of a driving-shaft, a series of grinding-rings, a series of rolls carried by said shaft and imparting rotary movement to said rings, supplemental shafts, a series of rolls supported on each of said shafts coacting with said rings and a frame having openings in which 95 the bearings of said shafts are situated, and means for preventing the material from passing out of the outer sides of said rings, substantially as described.

9. The combination in a pulverizing-mill, 100 of a driving-shaft, a series of independent grinding-rings, a series of rolls carried by said shaft and imparting rotary movement to said rings, supplemental shafts, a series of rolls supported on each of said shafts coacting 105 with said rings and a frame having openings in which the bearings of said shafts are situated, and spring-actuated devices for said bearings to force the last-mentioned rolls against said rings, substantially as described.

10. The combination in a pulverizing-mill, of a driving-shaft, a series of independent grinding-rings, a series of rolls carried by said shaft and imparting rotary movement to said rings, supplemental shafts, a series of rolls supported on each of said shafts coacting 115 with said rings and a frame having openings in which the bearings of said shafts are situated, and spring-mounted devices also located within the openings in said frames for forcing the last-mentioned series of rolls against said rings, substantially as described.

11. The combination in a pulverizing-mill, of a grinding-ring, a roll within and imparting rotary movement directly to said ring, a main frame having recesses therein formed at an angle to each other, bearings movably held in each recess, shafts supported by said

bearings, each shaft having a grinding-roll coating with said ring, and spring-mounted means located in said recesses and coating with said bearings for holding them with 5 their rolls in grinding contact with said ring, substantially as described.

12. The combination in a pulverizing-mill, of a series of independent grinding-rings, a series of rolls within and imparting rotary 10 movement to said rings, a main frame having recesses therein formed at an angle to each other, bearings movably held in each recess, shafts supported by said bearings, each shaft having a series of rolls coating with the said 15 series of rings, and means for holding the last-mentioned series of rolls in grinding contact with said series of rings, substantially as described.

13. The combination in a pulverizing-mill, 20 of a series of independent grinding-rings, a series of rolls within and imparting rotary movement to said rings, a main frame having recesses therein formed at an angle to each other, bearings movably held in each recess, 25 shafts supported by said bearings each shaft having a series of rolls coating with the said series of rings, and spring-mounted means for holding the last-mentioned series of rolls in grinding contact with the said series of 30 rings, substantially as described.

14. The combination in a pulverizing-mill, of a series of independent grinding-rings, a series of rolls within and imparting rotary movement to said rings, a main frame formed 35 in two parts located on opposite sides of said grinding rolls and rings, said frame having recesses therein, bearings movably mounted within said recesses, shafts in said bearings, and grinding-rolls on each of said shafts 40 within the aforesaid grinding-rings, and means for causing material to escape through the series of openings, substantially as described.

15. The combination in a pulverizing-mill, 45 of a series of independent grinding-rings, a series of rolls within and imparting rotary movement to said rings, a main frame formed in two parts located on opposite sides of said grinding rolls and rings, said frame having 50 recesses therein, spring-mounted bearings movably mounted within said recesses, shafts in said bearings, and grinding-rolls on each of said shafts within the aforesaid grinding-rings, substantially as described.

16. In a pulverizing-mill, the combination 55 of a rotatable grinding-ring, a roll surrounded by said ring and imparting rotary movement thereto, a grinding-roll, and a rotary sieve rotatable around said roll and ring and having means for returning the unsifted material to said roll and ring to be reground, substantially as described.

17. In a pulverizing-mill, the combination 65 of a grinding-ring a roll surrounded by and imparting rotary movement to said ring, a

grinding-roll, a hopper feeding material to said ring and roll and a rotary sieve rotatable around said ring and roll and having means for returning the unsifted material to said hopper to be again delivered to said 70 grinding ring and roll, substantially as described.

18. In a pulverizing-mill, the combination 75 of a grinding-ring, a roll within and imparting motion to said grinding-ring, grinding-rolls also supported within said ring and held in grinding contact therewith, and a rotary sieve rotatable around said rolls and ring and having means for returning the unsifted material to said rolls and ring, substantially as described.

19. In a pulverizing-mill, the combination 80 of a series of grinding-rings, a series of rolls within and imparting motion to said grinding-rings, grinding-rolls also supported within 85 said rings and held in grinding contact therewith, and a rotary sieve rotatable around said rolls and rings and having means for returning the unsifted material to said rolls and rings, substantially as described.

20. In a pulverizing-mill, the combination 90 of a grinding-ring, a roll within and imparting motion to said grinding-ring, grinding-rolls also supported within said ring and held in grinding contact therewith, and a rotary sieve rotatable around said rolls and ring and having pockets for returning the unsifted material to said rolls and ring, substantially as described.

21. In a pulverizing-mill, the combination 95 of a grinding-ring, a roll within and imparting motion to said grinding-ring, grinding-rolls also supported within said ring, a rotary sieve rotatable around said rolls and ring and provided with means for returning the unsifted material to said rolls and ring, said sieve having an internal gear, and a gear meshing with said internal gear for rotating the sieve, substantially as described.

22. In a pulverizing-mill, the combination 100 of a grinding-ring, a roll within and imparting motion to said grinding-ring, a shaft for imparting motion to said roll, a rotary sieve rotatable around said roll and ring and having means for returning the unsifted material thereto, and gearing driven by said shaft for rotating said rotary sieve, substantially as described.

23. In a pulverizing-mill, the combination 105 of a grinding-ring, a roll within and imparting movement to said ring, a hopper feeding material between said roll and ring, and a rotary sieve rotatable around said roll and ring and having means for returning the unsifted material to said hopper, substantially as described.

24. In a pulverizing-mill, the combination 110 of a grinding-ring, a roll within said ring, a hopper on each side of said roll and ring to feed material thereto, and a rotary sieve ro- 115

tatable around said roll and ring and having means across the sieve at the outside margin thereof for returning the unsifted material to said hoppers, substantially as described.

5 25. In a pulverizing-mill, the combination of a grinding-ring, a roll within said ring, a hopper on each side of said roll and ring to feed material thereto, and a rotary sieve rotatable around said roll and ring and having 10 pockets across the sieve at the outside margin thereof for returning the unsifted material to said hoppers, substantially as described.

15 26. The combination in a pulverizing-mill, of a series of revolving rings, a series of rolls located within and imparting rotary movement to said rings, a series of spring-mounted grinding-rolls also coacting with said rings, and means for preventing the crushed material from passing out of the outer sides of the 20 outside rings, substantially as described.

25 27. The combination in a pulverizing-mill, of a series of revolving rings, a series of rolls located within and imparting rotary movement to said rings, a series of spring-mounted grinding-rolls also coacting with said rings, and rings or plates for preventing the crushed material from passing out of the outer sides of the 30 outside rings, substantially as described.

30 28. A pulverizing-mill, having, in combination, a plurality of independent grinding-rings located side by side and having internal grinding-surfaces, and grinding elements co-operating therewith, one of the rings being located with its grinding-surface lower at its 35 lower portion than the grinding-surface of

the adjacent ring so as to receive material from the adjacent ring for regrinding, substantially as described.

29. A pulverizing-mill, having, in combination, a plurality of independent rotating grinding-rings having concentric internal grinding-surfaces, means for rotating the rings, and grinding elements co-operating therewith, the internal diameter of one ring 40 being greater than that of an adjacent ring 45 so that the former ring may receive material from the latter ring for regrinding, substantially as described.

30. A pulverizing-mill, having, in combination, a plurality of independent concentric grinding-rings of different internal diameters located side by side, and a plurality of rolls 50 engaging the interior surfaces of the rings, the rolls being of different diameters and being arranged to rotate concentrically, substantially as described.

31. A pulverizing-mill, having, in combination, a plurality of rotating rings, located 55 side by side with an escape-opening between 60 for pulverized material, and means for rotating the rings with different peripheral velocities so that the lateral surfaces of the rings have a differential motion facilitating the passage of material therebetween, substantially as described.

Signed by me at Washington, District of Columbia, this 9th day of September, 1904.

WILLIAM S. OSBORNE.
